UNITED STATES PATENT OFFICE

ALFRED A. GOHN, OF WARREN, PENNSYLVANIA

FUEL-GASIFYING DEVICE

Application filed July 31, 1926. Serial No. 126,211.

This invention relates to an improved fuel gasifying device for internal combustion engines, and seeks, among other objects, to provide means which will function over a wide range of engine speeds for supplying the engine with a cool, dry, combustible fuel gas.

The invention seeks, as a further object, to provide a device wherein the liquid fuel will be thermally vaporized in the presence of a restricted quantity of air, wherein the fuel vapor thus produced will be subsequently heated, and wherein the vapor will then be diluted with auxiliary fresh air to form a cool, properly balanced fuel mixture.

15 A further object of the invention is to provide a device embodying a liquid fuel feed valve which may be adjusted for low engine speed.

Another object is to provide a device embodying a liquid fuel feed valve which may be adjusted for high engine speeds.

Still another object is to provide a device embodying a primary air valve adjustable for low engine speed.

25 And the invention seeks, as a still further object, to provide a device which may be readily installed and which will be well adapted for general use.

Other objects of the invention not specifically mentioned in the foregoing will appear during the course of the following description.

In the accompanying drawings:

Figure 1 is a plan view showing my improved gasifying device applied.

Figure 2 is a front elevation of the device.

Figure 3 is an enlarged sectional view on the line 3—3 of Figure 1, looking in the direction indicated by the arrows.

40 Figure 4 is a horizontal sectional view on the line 4—4 of Figure 3, looking in the direction indicated by the arrows, this view particularly showing the primary air valve.

45 Figure 5 is a transverse sectional view on the line 5—5 of Figure 3, looking in the direction indicated by the arrows, this view particularly showing the ports of the liquid fuel feed valves.

50 Figure 6 is a detail sectional view on the

line 6—6 of Figure 3, looking in the direction indicated by the arrows.

Figure 7 is a fragmentary sectional view taken through the inlet end of the intake manifold and showing the auxiliary air valve 55 as well as the aspirating nozzles in said manifold.

Figure 8 is a detail sectional view taken at substantially a right angle to Figure 3, and particularly showing the arm on one of the 60 fuel feed valves.

Figure 9 is a detail perspective view showing the supporting collar for the primary air valve.

In carrying the invention into effect, I employ an exhaust manifold 10 which is provided with inlets 11, and disposed between the inlets located near the ends of said manifold are intake elbows 12 connected with such inlets by webs 13 which are formed with sleeves 14. As shown in Figure 1, these sleeves are designed to receive bolts 15 connecting the manifold with an engine, conventionally indicated at 16, the inlets 11 of the manifold communicating with the exhaust ports of the engine block and the elbows 12 communicating with the intake ports of the block. Extending over the exhaust manifold is an intake manifold 17 which, as seen in Figure 6, is provided with outlets 80 18 fitting in the elbows 12, and extending through the manifold and through said elbows are bolts 19 rigidly connecting the manifold with said elbows.

Near the outlet end thereof, the exhaust 85 manifold 10 is provided, as seen in Figure 3, with ears 20, and fixed to said manifold is a fuel bowl 21, at the lower end of which is a gasifying chamber 22 having ears 23 mating with the ears 20. Extending through 90 said ears are screws or other fastening devices 24 detachably connecting the fuel bowl with the exhaust manifold. Thus, as will be seen, the top wall of the exhaust manifold provides what may well be termed a hot plate 95 25 which forms the bottom wall of the gasifying chamber 22, since, when the engine is in operation, the plate 25 will be heated by the exhaust gases flowing through the manifold. Rising from the bottom wall of 100

the bowl axially thereof is a sleeve 26 having an internal shoulder 27, and fitting over said sleeve is a closure plate 28 for the bowl. Screwed upon the upper end of the sleeve is a split collar 29 securing the closure plate in position and, as best seen in Figure 9, this collar is provided with radial ears 30 accommodating a set screw 31 which may be tightened for securing the collar in adjusted position. Extending from the collar is a radial arm 32 and upstanding from said arm is a post 33. The closure plate 28 is provided with a liquid fuel inlet 34, the inner end of which slidably receives a needle valve 35, and swingingly mounted upon said plate is a float 36, the hinge arm 37 of which is disposed to engage the valve 35 for closing the valve as the float rises within the bowl. Thus, as will be appreciated, the level of the liquid fuel within the bowl will be maintained relatively constant.

Formed on the sleeve 26, externally thereof, is a fuel passage 38 which originates near the bottom of the bowl but enters the sleeve 25 at a point below the liquid level of the bowl, and rotatably fitting in said sleeve is a tubular fuel feed valve 39 resting at its lower end on the shoulder 27 of the sleeve. This valve is provided near its lower end with a port 40 30 adapted to be brought into register with the passage 38, and formed on the upper end of the valve is a flange 41 from which projects, as seen in Figure 8, a radial arm 42. Rising from the closure plate 28 of the bowl at opposite sides of said arm, as particularly seen in Figure 4, are posts 43, and screwed through said posts to coact at their inner ends with said arm are set screws 44.

Rotatably fitting within the valve 39 is a tubular fuel feed valve 45 which is provided 40 near its lower end with a port 46 adapted to be brought into register with the port 40 of the former valve, and screwed upon the upper end portion of the valve 45 is a split collar 47, the radial ears of which carry a set screw 48 which may be tightened for securing the collar in adjusted position, the collar resting against the flange 41 of the valve 39 for rotatably supporting the valve 45 at the 45 desired elevation. Projecting from said valve is a lever 49, and formed on the upper end of the valve is a sector-shaped head 50 and as will be observed, the central passage 51 of the valve opens through the curved peripheral edge of said head. Fixed to the upper end of the post 33 of the collar 29 is a flat spring valve 52 which is curved to fit the peripheral edge of the head 50 and, when the valve 45 is closed, as shown in Figures 4 and 5, overlies the passage 51. This passage is provided for admitting primary fresh air to the gasifying chamber 22 so that when the valve 45 is closed the supply of primary air to said chamber will be cut off. However, as 55 the valve 45 is turned in a clockwise direction

toward open position and the port 46 of said valve is brought more and more into register with the port 40 of the valve 39, the end of the passage 51 at the peripheral edge of the head 50 will be moved from beneath the valve 52 so that a correspondingly increasing volume of primary air will be admitted to the gasifying chamber. As will be appreciated, the liquid fuel in the bowl 21 will, when the valve 45 is opened, rise through the passage 38 to flow through the port 40 of the valve 39 and thence through the port 46 of the valve 45 to enter the sleeve 26 and flow into the gasifying chamber 22. However, the passage 51 is of a diameter to admit only a restricted maximum quantity of fresh air to the chamber 22 so that the gasification of the liquid fuel in said chamber will take place in the presence of a restricted quantity of air only and, as the valve 45 is closed and the outer end of the passage 51 is again brought beneath the valve 52, the flow of primary air to said chamber will be quickly cut off by said valve.

Attention is now directed to the fact that by turning the set screw 44, the arm 42 of the valve 39 may be swung for rotatably setting the valve to dispose either a greater or a smaller portion of the port 40 thereof in register with the passage 38 so that the quantity of fuel flowing through said passage and through the port 40 for low engine speed may be readily regulated. Furthermore, attention is directed to the fact that by adjusting the collar 47 on the valve 45, said valve may be either raised or lowered to dispose either a greater or less portion of the port 46 of said valve in the plane of the port 40 of the valve 39 to register with the latter port. Thus, the valve 45 may be readily set to regulate the quantity of fuel flowing through the passage 38 and the ports 40 and 46 of the valves 39 and 45 at high engine speeds. Also, it is to be noted that by rotatably adjusting the collar 29 on the upper end of the sleeve 26, the valve 52 may be set with respect to the normal closed valve position of the outer end of the primary air passage 51 for varying the instant of opening and closing of said passage and consequently regulating the quantity of fresh air initially admitted to the gasifying chamber 22 as the valve 45 is opened.

Frictionally held in the outer end portion of the intake manifold 17, as seen in Figure 7, are spaced aspirating nozzles 53 and 54, the latter of which is somewhat longer than the former nozzle, and connecting the gasifying chamber 22 with said manifold is a pipe 55 entering the manifold at a point close to the mouth of the nozzle 53, between said nozzle and the nozzle 54. As shown in Figure 2, the pipe 55 lies against the exhaust manifold 10 so that said pipe will be heated by the manifold and, if desired, the pipe 55 may be arranged to extend into the manifold so as

to be brought into direct contact with the heated exhaust gases flowing therethrough. Rotatably mounted in the intake manifold 17 near the outer end thereof is an auxiliary air control valve 56, to the upper end of which is secured a double-ended lever 57, and rising from one end of said lever is a post 58 on which is formed a shoulder 59. Pivotally connected at one end with the lever 49 of the fuel feed valve 45 is a rod 60, the opposite end of which, as seen in Figure 1, is provided with a yoke 61 slidably fitting over the upper end of the post 58 to rest against the shoulder 59, and connected at one end to the lever 49 and 15 at its opposite end to said post is a spring 62 normally holding the post at the inner end of said yoke. Formed on the rod at the base of the yoke is an ear 63 to which is pivotally connected a manually operable priming rod 64, and pivotally connected to the end of the lever 57 opposite the post 58 is a manually operable throttle rod 65. Thus, as will be seen, as the throttle rod 65 is moved forwardly for opening the auxiliary air valve 56, the 20 fuel feed valve 45 will be coincidentally opened by the rod 60 so that these valves will thus operate in unison. However, when starting the engine, the rod 64 may, while the auxiliary air valve 56 remains closed, be pulled rearwardly for shifting the rod 60 endwise and opening the fuel feed valve 45 independently of the auxiliary air valve. Thus, an increased flow of liquid fuel will be admitted to the gasifying chamber 22 to provide a rich mixture and, of course, upon release of the rod 64, the valve 45 will be returned by the spring 62.

As will now be seen in view of the foregoing, when the valves 45 and 56 are opened, 40 engine suction will be directly communicated from the intake manifold 17 through the pipe 55 to the gasifying chamber 22 so that liquid fuel will be aspirated from the bowl 21 into said chamber along with a restricted 45 quantity of primary air, to strike the hot plate 25. The liquid fuel will thus be thermally gasified and mixed with the primary air to form a rich fuel gas. This gas will then be heated in said chamber and further heated 50 and dried as the gas flows through the heated pipe 55 to the intake manifold, when the gas will be diluted by the auxiliary fresh air entering past the valve 56, to form a dry fuel mixture cooled by the auxiliary air. Premature expansion of the mixture or overheating 55 of the engine will thus be avoided.

Having thus described the invention, what I claim is:

1. A fuel gasifying device including an 60 exhaust manifold, an intake manifold, a liquid fuel supply bowl having a gasifying chamber fixed to the exhaust manifold and heated thereby, a tubular valve controlling the flow of liquid fuel from said bowl to said chamber, a second valve journaled in said first

mentioned valve and controlling the feed of the fuel to said chamber, the latter valve being provided with a primary air passage for admitting a restricted quantity of primary air to said chamber to mingle with the vaporized liquid fuel and form a fuel gas, means for conducting the fuel gas from said chamber to the intake manifold, a valve controlling the admission of auxiliary air to the intake manifold to mingle with the fuel gas and form a fuel mixture, means for holding the first named valve in adjusted position to govern the inlet of fuel, and means connecting said feed valve and said auxiliary air valve to operate in unison. 70

2. A fuel gasifying device including an exhaust manifold, an intake manifold, a liquid fuel supply bowl having a gasifying chamber fixed to the exhaust manifold and heated thereby, a tubular valve controlling the flow of liquid fuel from said bowl to said chamber, a second vertically adjustable valve journaled in said first mentioned valve and controlling the feed of the fuel to said chamber, the latter valve being provided with a primary air passage for admitting a restricted quantity of primary air to said chamber to mingle with the vaporized liquid fuel and form a fuel gas, means for conducting the fuel gas from said chamber to the intake manifold, a valve controlling the admission of auxiliary air to the intake manifold to mingle with the fuel gas and form a fuel mixture, means connecting said feed valve and said auxiliary air valve to operate in unison, and means for adjusting said first mentioned valve to vary the minimum quantity of liquid fuel admitted to said chamber when said feed valve is fully open. 80

In testimony whereof I affix my signature. 85
